UNITED STATES PATENT OFFICE.

JOHN J. DELANEY, OF DETROIT, MICHIGAN.

SASH-CENTER.

1,137,706.

Specification of Letters Patent. Patented Apr. 27, 1915.

Application filed May 4, 1912. Serial No. 695,090.

To all whom it may concern:

Be it known that I, JOHN J. DELANEY, a citizen of the United States of America, residing at Detroit, in the county of Wayne 5 and State of Michigan, have invented certain new and useful Improvements in Sash-Centers, of which the following is a specification, reference being had therein to the accompanying drawings.

10 The invention relates to sash centers of that type in which the device may first be attached to the window sash, and then—together with the latter—placed in engagement with the window frame and secured in 15 position.

It is the object of the invention to simplify the construction and cheapen the manufacture; also, to obtain a stronger and more durable mechanical structure.

20 To this end, the invention consists in the construction as hereinafter set forth.

In the drawings,—Figure 1 is a horizontal section through the window frame and center, showing the sash turned in horizontal 25 position and substantially on lines $x-x$ of Fig. 3; Figs. 2 and 3 are elevations of the frame and sash members; Fig. 4 is a perspective view of the various elements associated with the frame and sash members in 30 the complete center construction; and Fig. 5 is a section substantially on line $y-y$ Fig. 3, showing the weather and light guard.

It is one of the objects of the invention to substitute for the cast metal constructions 35 which have been generally heretofore employed a construction the main elements of which may be formed by dies, thereby securing greater accuracy and mechanical perfection without a material increase in cost.

40 As shown, A is the securing plate of the frame member, which is struck up from sheet metal and is provided with apertures B for the securing screws, a central aperture C for receiving the pivot pin, and a circular series of recesses D surrounding said 45 central pin and adapted for engaging ball ratchets. There is also preferably provided centrally and longitudinally of the member A a groove E having an annular central portion E' in which the weather and light guard is located.

F is the sash member, which is preferably of slightly less length than the member A and has squared ends, whereas the member 50 A is preferably provided with curved or segmental ends. The member F is centrally

apertured at G to correspond to the aperture C, and is provided with an annular groove H surrounding the aperture and communicating with the central longitudinally extending grooves I corresponding to the grooves E E' in the member A. The member F is further provided with apertures J therethrough, which are radially distant from the center of the aperture G equal to 60 the radius of the annular series of recesses D in the member A. There are also apertures K for screws or other securing means. 65

L is the pivot pin, which is formed with a head L' thereon and is adapted to be engaged with the aperture C of the member A, the head engaging a countersink surrounding said aperture.

M is a sleeve for engaging the pin L and around which is placed a spring N having 70 one end abutting against a flange M' on the sleeve.

O is a washer or apertured disk surrounding the sleeve M and against which the opposite end of the spring N bears.

80 P are balls engaging the apertures J and pressed by the washer O under the tension of the spring N into the sockets D of the member A.

Q is a spring washer interposed between 85 the washer O and the plate F, and R is a cotter pin engaging an aperture L² in the pivot pin L and extending out beyond the same into an annular groove M² in the member M.

90 S is a light guard—preferably formed of resilient wire—bent to extend in the grooves E I and H E'. This member is in the form of a wire loop having its end portions S' bent into substantial parallelism and its central portion into a circular form which will fit in the grooves E' H. The portions on the opposite sides of the center of this member are, however, sprung out of alignment so as to overlap each other, and consequently 100 when the member is placed in the grooves of the members A F it will form a guard intercepting the light and the direct path of air or dust.

105 The construction of the parts being as above described, in assembling the center the pin L is placed into engagement with the aperture C of the member A'. The member S is then placed in the grooves E E', after which the member F is also sleeved 110 upon the pin and placed in contact with the member A. Balls P are next placed in the

apertures J. The washers Q O are sleeved upon the pin, the latter to bear against the balls P. The sleeve M is placed in position with the spring N surrounding the same, and 5 pressure is then applied to said sleeve to compress the spring sufficiently for the insertion of the cotter pin R. When this is engaged the parts will be locked together and the balls P are resiliently pressed 10 through the apertures J into engagement with the sockets D. The center may then be mounted upon the sash of the window by boring an aperture T of sufficient size to receive the parts and securing the plate F to 15 the sash. The sash is then placed in the window frame, and when the member A is properly positioned it may be secured by turning the sash at an angle, so as to expose the apertures B for the screws.

20 In operation, whenever the sash is adjusted upon its pivot the balls P will be forced out of the sockets D against the washer O, and the tension of the spring N bearing thereon, but as soon as they pass 25 into registration with another socket D the spring will immediately cause reengagement. The guard member S will be slightly sprung by the pressure of the plates A F on opposite sides thereof, and will form a 30 suitable light guard.

The plates A F being formed by dies will be absolutely accurate and true, and therefore the operation of centers of this construction will always be the same, which is 35 not true of constructions formed of unmachined cast parts.

What I claim as my invention is,—

1. A sash center comprising a plate formed with a central aperture there being a groove 40 surrounding said aperture, having portions extending longitudinally of the plate and opening through its ends, means for attaching the plate to a sash, a pin seated in the aperture of the plate, a second plate formed 45 with an aperture, and a groove which surrounds said aperture, having portions extending longitudinally of the plate and opening through its ends whereby the same will aline with the groove of the first men- 50 tioned plate, resilient means embracing the pin and contacting with the second men-

tioned plate and acting to normally force the plates together, and a member constituting a dust guard formed of a strand of resilient material disposed within the alining grooves of the plates. 55

2. A sash center including a plate secured to the sash and provided with a central opening, there being a series of ball sockets surrounding said opening, a second plate, a pin rigidly supported by the first plate and extending through the second plate, a sleeve mounted on said pin, resilient means for normally spacing said sleeve from the second mentioned plate, a washer 60 slidably mounted on the sleeve, resilient means for normally forcing said washer toward said second mentioned plate, said plate being provided with a series of openings which aline with the ball socket of the first 65 mentioned plate, balls arranged in said opening, said washer contacting with said balls. 70

3. A sash center including a plate supported by the sash, a second plate carried by the window frame, a pin supported by the first mentioned plate and extending through the second plate within a recess formed in the frame, a sleeve mounted on said pin, said sleeve being provided terminally with a flange, a stop carried by the pin and contacting with the flange to maintain the sleeve on the pin, a resilient member interposed between the sleeve and the second mentioned plate, a washer slidably mounted on the sleeve, a coiled spring embracing the sleeve, one of the terminal convolutions of said spring contacting with the flange of the sleeve, its other terminal convolution contacting with the washer, and 80 balls operating through openings formed in the second mentioned plate and engaging in recesses formed in the first mentioned plate, said washer contacting with said balls to maintain the same in contact with the first 85 mentioned plate. 90

In testimony whereof I affix my signature in presence of two witnesses.

JOHN J. DELANEY.
